(57) **CLAIM**

The ornamental design for a surgical microscope, as shown and described.

DESCRIPTION

FIG. 1 is a perspective view of a first embodiment of a surgical microscope showing our new design;
FIG. 2 is a front elevational view thereof;
FIG. 3 is a right side elevational view thereof;
FIG. 4 is a left side elevational view thereof; and
FIG. 5 is a top plan view thereof.

FIG. 6 is a partially enlarged perspective view thereof along the lines 6-6 and 6'-6' of FIG. 3; and,

FIG. 7 is a partially enlarged top plan view thereof along the lines 7-7 and 7'-7' of FIG. 5.

The even-dash broken lines show portions of the surgical microscope that form no part of the claimed design. The dot-dash broken lines define boundaries of the claimed design and form no part thereof.
